(57) **CLAIM**

I claim the ornamental design for a container with closure, as shown and described.

DESCRIPTION

FIG. 1 is a front elevational view of the container with closure.

FIG. 2 is a rear elevational view of the container with closure.

FIG. 3 is a top plan view of the container with closure, the bottom of the package being without ornamentation and forming no part of the claimed design.

FIG. 4 is a left side elevational view of the container with closure as illustrated in FIG. 1.

FIG. 5 is a right side elevational view of the container with closure as illustrated in FIG. 1; and,

FIG. 6 is a perspective view of the container with closure.
